SHIRT

John Lodge Shaw, Crouch End, London, England

Application July 28, 1934, Serial No. 737,372
In Great Britain July 31, 1933

1 Claim. (Cl. 2—117)

This invention relates to shirts mainly for sports use, by means of which braces or a belt worn to support the wearer's trousers or a skirt can be concealed from view.

5 The object of the invention is to provide a shirt of this kind of simple design and which requires no adjusting or manipulation by the wearer.

For the above purpose, the shirt has a depending external shallow pleat at and around the 10 waist, concealing, by extending over, slits through which the buttonholed tabs of braces worn beneath the shirt can extend to the buttons of trousers. According to the invention, the pleat is formed permanently in the material of the 15 shirt by being secured, for example by stitching, along the upper border to the body portion of the shirt.

The provision of an overhanging pleat around the waist of a shirt is advantageous apart from 20 enabling braces or a belt to be concealed. The three thicknesses of material around the waist formed by the fold protect the lumbar regions of the wearer and if the trousers or other garments are self-supporting or are supported by a belt 25 the fold conceals the top of the garment and imparts a neat appearance to the wearer's apparel.

The invention is illustrated by way of example on the accompanying drawing, in which:—

Fig. 1 is a front view of a shirt, and 30
35 Fig. 2 is a dodged section through the shirt on line 2—2 at the back and line 2a—2a at the front.

a is a shirt of usual sports pattern except that an excess of material is provided in the direction 35 of the length of the body portion of the shirt. This excess length of material is folded into a pleat b around the waist portion of the shirt a,

and such pleat b is rendered permanent by a line of fine stitching c around the top border thereof.

Slits d are formed in the material of the shirt a beneath the pleat b through which slits the tabs of braces may be passed for securing to 5 trouser buttons.

A buttonholed tab e shown in dotted lines on Fig. 1 may also be provided attached to the shirt a by sewing centrally of the front thereof beneath the pleat b. This tab e when secured to 10 a trouser button will prevent the shirt a from working upwards owing to movement of the wearer.

In the case of a knitted garment, alternatively to rendering the pleat permanent by stitching, 15 the excess of material may be secured at the upper border by interknitting juxtaposed rows of stitches in the several thicknesses of material, along the line c Fig. 1. Such a process is known as "grafting". 20

The pleat may be constricted at the bottom edge by an elastic band or may merely hang free over the waist band of the trousers, although for appearance sake it preferably more or less snugly fits the wearer. 25

The invention is obviously applicable to ladies' and children's shirts.

I claim:

In a shirt garment, a body portion having a three-ply transverse pleat formed in the material 30 of and at the waist of said body portion, said three-ply pleat having slits in the innermost ply and concealed by the outer plies thereof, and stitches extending through the three plies of said pleat at the upper fold thereof and above said 35 slits.

JOHN LODGE SHAW.
